UNITED STATES PATENT OFFICE.

SAMUEL MODERN AND MAX MOSKOWITZ, OF NEW YORK, N. Y.

DESIGN FOR A SUITCASE-HANDLE.

57,143.

Specification for Design. Patented Feb. 22, 1921.

Application filed July 31, 1920. Serial No. 400,550. Term of patent 3½ years.

To all whom it may concern:

Be it known that we, SAMUEL MODERN and MAX Moskowitz, citizens of the United States, residing at New York, in the county of New York and State of New York, have invented a new, original, and ornamental Design for Suitcase-Handles, of which the following is a specification, reference being had to the accompanying drawing, forming part thereof.

In the drawings:—

Fig. 2, is a side elevation thereof, and

Fig. 3, is an end elevation of the same.

We claim:—

The ornamental design for a suitcase handle, as shown.

SAMUEL MODERN.
MAX MOSKOWITZ.
